R. R. Moffatt

UNITED STATES PATENT OFFICE.

RICHARD R. MOFFATT, OF BROOKLYN, NEW YORK, ASSIGNOR TO THE BROOKLYN ELECTRIC CONSTRUCTION COMPANY, OF SAME PLACE.

REVERSIBLE SWITCH FOR INCANDESCENT LAMPS.

SPECIFICATION forming part of Letters Patent No. 333,657, dated January 5, 1886.

Application filed February 8, 1882. Serial No. 52,160. (No model.)

To all whom it may concern:

Be it known that I, RICHARD R. MOFFATT, of the city of Brooklyn, county of Kings, State of New York, have invented new and useful 5 Improvements in Reversible Switches for Incandescent Lamps; and I do hereby declare the following to be a full and exact description of the same, reference being had to the accompanying drawings, and to the letters of reference marked thereon.

This invention relates to that class of electric lamps known as the "incandescent" system, in which a carbon conductor of low conductivity is made to give out light by electrical incandescence within a sealed glass globe that is exhausted of air or in which is placed a preserving gas, and its object is to render the carbon more stable and enduring for the purpose of prolonging the life of the lamp.

20 In electric lamps, wherein the carbon filament is used to give light by its incandescence, it has been found that a gradual displacement or movement of the carbon itself takes place, to which has been applied the 25 term "electrical carrying." This moving or carrying of the carbon molecules is from the negative to the positive end of the carbon, and the amount of such carrying depends upon the resistance of the filament, the electro-motive force between the clamping of the electrodes, the degree of incandescence, and the state of the vacuum, which has been 30 found to be the prolific cause of the final disruption and destruction of the carbons used 35 in high vacuo.

My invention consists in providing an incandescent electric lamp or lamps with a circuit-reverser that will change the course of the electric current within the lamp or lamps 40 every time the circuit is closed therein. It also consists in a novel device for changing the course of the electric current through the lamp by means of the circuit-controller; also, the use of an adjustable reflector, and in the 45 devices hereinafter specified.

In the drawings, Figure 1 is a vertical section of a lamp constructed in accordance with my invention. Fig. 2 is a cross-section of the

same, taken on the line $x-x$, Fig. 1. Fig. 3 is a cross-section taken on the line $x'-x'$, Fig. 1. 50 Fig. 4 is a cross-section taken on the line $x''-x''$, Fig. 1. Fig. 5 is a base view of the inner lamp-holder.

Similar letters of reference indicate like parts in the several figures.

A is a glass globe or receiver which is exhausted of air.

D is an inclosed chamber, located in the stem or neck of the receiver, and which is also exhausted of air. $a-a$ are leading-in wires, 60 which are fused or cemented to the glass through which they pass. The inner terminals of these wires support the incandescent carbon filament a' . The outer terminals of these wires are made to extend upward on 65 the outside of the neck or stem of the receiver A, as shown in Fig. 1.

C is the lamp-socket, provided with a central stem or prolongation, C', on the lower end of which is secured a thumb-piece or key, S, 70 by means of which the socket C may be rotated.

D is an outer socket, made so as to receive the lamp-socket C. The stem C' extends through an opening in the center of the base 75 of the socket-piece D.

The two socket-pieces C and D are made of vulcanite or other suitable non-conducting material.

v is a spiral spring, located between the 80 base of the socket-piece D and the key S, and is intended to keep the flange on the upper part of the socket C down upon the upper edge of the socket-piece D, in order to insure a good pressure-contact between the metal 85 parts c and e .

$d-d$ are small inclined projections or lugs, located within the socket D, as shown in Figs. 1 and 4.

d' is a spring, one end of which is secured to 90 the base of the socket-piece C, as shown in Figs. 1 and 5.

e is a metallic strip, secured to the under part of the flange of the socket-piece C. A portion of this metal strip extends to the inner surface of said socket, and makes contact 95

- with the wires *a a* when the lamp is in position, as shown in Fig. 1. The strips *c c* are made to extend almost entirely around the socket *C*, as shown in Fig. 3.
- 5 *e e* are metallic studs located upon the edge of the socket *D*, as shown in Figs. 1 and 2. To these studs are secured wires *e' e'*, to the outer terminals of which the main or circuit wires are attached.
- 10 *D'* is a projecting portion of the socket *D*, by which the latter is secured to the fixture. *m* is a teat or projection on the top of the globe or receiver *A*.
- 15 *m'* is a metallic reflector having an indentation, *n*, in its center, by means of which it is held in position upon the teat or projection *m*, as shown in Fig. 1. The reflector is provided with one or more perforations, *m''*, located near its rim. By the use of this adjustable reflector 20 *m'* the light-rays are thrown downward. If desired, the reflector may be used upon the side of the lamp by placing the perforation *m''* (instead of the indentation *n*) over the teat or projection *m*. When the reflector is thus 25 applied to the side of the lamp, the light-rays can be concentrated in a great degree in any desired horizontal direction; or it may be used to cast a shade instead.
- 30 As the metallic plates *c c* extend almost around the circumference of the lamp, as shown in Fig. 3, leaving only a sufficient space to insure the breaking of the circuit, the lamp may be turned upon its longitudinal axis, so that the maximum light-giving surface of the carbon filament can be utilized in any desired direction.
- 35 In the operation of this invention the lamp is turned by means of the key *S* upon its longitudinal axis in one direction only. A pawl 40 spring, *d'*, engaging with projections *d d*, prevents its rotating in the other direction. In this movement the metal pieces *e e* and *c c* make and break contact, thus completing the circuit through the lamp when the parts *c* and 45 *e* are in contact, or breaking said circuit when they are not in contact, as will be understood. As the current always enters through one of the wires *e'*, it follows that it will travel the carbon filament in a reverse direction every 50 time the lamp is turned to break and close the circuit again. This operation causes a reversal of the current through the carbon filament, and consequently a reversal of the electrical carrying therein, thus preventing to 55 a great extent the injurious results that are caused by the current continuously passing through the carbon filament in the same direction.
- 60 The details of this invention can be modified and applied in various advantageous ways and still retain the main features for the purposes intended. The means that change or reverse the course of the current through the carbon filament may be made to operate independently of the means used for breaking or 65 closing the circuit.

I am aware that reversing switches have been used in arc lamps, but this I disclaim, as my invention is for use only in incandescent electric lamps, in which a fine carbon filament 70 is made luminous in vacuum or in a receiver containing a preserving-gas, the purpose being simply to prolong the life of the filament by reversing the course of the electric current through the filament, as described, thus preventing the injurious results caused by the electric disturbance or carrying off of the molecules of the filament when the current passes always in one direction.

Having thus fully described the nature, construction, and operation of my invention, what I claim as new, and desire to secure by Letters Patent, is—

1. The combination of an electric incandescent lamp and a reversing-switch. 80
2. An incandescent electric lamp, substantially as described, provided with means for closing and breaking the circuit that will change or reverse the course of the current through the carbon filament each time the 85 circuit is closed therein, substantially as and for the purpose specified.
3. An incandescent electric lamp provided with means for closing and breaking the circuit through said lamp by rotating or turning 90 the lamp upon its longitudinal axis, substantially as herein specified.
4. An incandescent electric lamp provided with means for breaking and closing the circuit therein, and that will also change or reverse the course of the current through the carbon filament each time the said circuit is closed in said lamp by rotating the lamp upon its longitudinal axis, substantially as and for the purpose specified. 95
5. In an incandescent electric lamp, the combination of the vacuum bulb *A*, within which is a carbon filament of high resistance forming a continuous unbroken conductor that will give out light by its entire incandescence, 100 with means for changing or reversing the current therein, substantially as described, and for the purpose specified.
6. In an incandescent electric lamp, the combination of the receiver *A*, rotating socket *C*, 105 having a central spindle, *C'*, the stationary socket *D*, and the spring *v*, substantially as and for the purpose specified.
7. An incandescent electric lamp provided with means, substantially as described, for 110 permitting the receiver *A* to be turned upon its longitudinal axis (to a limited distance) without breaking the circuit, for the purpose of utilizing the maximum light-giving surface of the carbon filament in any desired direction, substantially as specified. 115
8. In an incandescent electric lamp, the combination of the receiver *A*, rotating socket *C*, stationary socket *D*, the lugs or projections *d*, and the spring or ratchet *d'*, substantially 120 as herein specified.
9. In an incandescent electric lamp, the re- 125

ceiver A, having a teat m , in combination with an adjustable reflector, m' , provided with a central indentation, n , or its equivalent, substantially as and for the purpose herein specified.

10. In an incandescent electric lamp, the receiver A, provided with a teat-like projection, m , in combination with an adjustable

reflector, m' , having a central indentation, n , and one or more perforations, m'' , substantially as and for the purpose specified.

R. R. MOFFATT.
